Filed Oct. 5, 1966, Ser. No. 584,582
5 Claims. (Cl. 15—150)

ABSTRACT OF THE DISCLOSURE

A mop holder for a multi-filament mop element having a fixed jaw and a pivotal jaw adjustably mounted with respect to the fixed jaw to accommodate various thicknesses of mop elements. A lever actuated $\text{\textcircled{z}}$ -shaped catch engages the free end of the pivotal jaw to maintain it in mopping position.

Specification

Mops comprising a multitude of flexible, liquid-absorbent filaments are commonly employed for swabbing floors and other soiled surfaces with liquid cleaning agents, i.e. soap solutions and the like. Commercially available multi-filament mops commonly comprise two banks or arrays of filaments, said two banks being on respective sides of a central web portion of the mop. Holders for multi-filament mops invariably comprise a forward base that is transversely disposed with respect to an elongate handle. Because the mop itself must necessarily be attached to the forward base in a fixed relationship therewith, many prior art workers have directed their efforts to a holder which includes a wholly-enclosed transversely-disposed slot positioned immediately rearwardly of the forward base, the width of the slot being about equal to that of the mop central portion. With the wholly-enclosed slot type mop holder the mop central web is positioned within the slot during use, and accordingly, it is necessary to insert one bank of filaments through the slot when attaching the mop to the holder, and conversely to withdraw a bank of filaments through the same slot in a direction normal to forward base when disengaging a worn or fouled mop. While the enclosed slot type mops are usually of simple and unitary economical construction, operational difficulty is invariably encountered with inter-bank filament tangling of the mop, it being impossible to withdraw the mop from a wholly-enclosed slot when filaments are tangled around the forward base. Accordingly, it is necessary for the operator to engage in the laborious and messy task of breaking or unknotting the inter-bank filament tangles before the mop can be disengaged from the holder.

Because of the difficulty encountered in removably disengaging tangled mops from enclosed-slot type mops, the art has developed several alternate types of mop holders. Invariably, however, these alternate embodiments have been deficient in one or more of the following respects: complex and expensive construction is involved; a multitude of separable and easily-lost parts are employed; cumbersome operation is involved for mop installation and disengagement; and it is difficult or impossible to adjust the holder for the various thicknesses of mops likely to be encountered.

It is accordingly a general object of the present invention to provide a mop holder device that overcomes the several disadvantages of the prior art.

It is a specific object of the present invention to provide a mop holder device wherein a tangled worn mop may be quickly and easily disengaged therefrom along the same transverse direction of the forward base rather than in a direction normal thereto.

It is another object of the present invention to provide a mop holder having a simple unitary construction com-

2

parable to that for enclosed slot type prior art holders, yet does not have the several disadvantages thereof.

It is another object to provide a mop holder device that will adjustably conform to several mop thicknesses.

5 It is a further object to provide a mop holder device that is economical to manufacture and repair utilizing readily available simple parts.

With the above and other objects and advantages in view, which will become more apparent as the description proceeds, the invention comprises the novel form, combination, and arrangement of parts as hereinafter more fully described, reference being had to the accompanying drawing wherein like numbers refer to like parts in the several views and in which:

10 FIGURE 1 is a front elevational view of the mop holder of the present invention.

15 FIGURE 2 is a side elevational view of the mop holder of the present invention.

20 FIGURE 3 is a sectional elevational view taken along line 3—3 of FIGURE 1.

25 FIGURE 4 is a sectional elevational view taken along line 4—4 of FIGURE 1.

The mop holder 10 of the present invention is attached to the forward end 9 of an elongate handle 8 as by means of a tight friction fit, or by the threaded engagement shown, or by any one of the equivalent means that are well known in the art. Mop holder 10 comprises a frame member extending forwardly of handle 8, said frame member including a first side 11, a second side 12, and an intervening base 13 attached to sides 11 and 12. Frame sides 11 and 12 preferably are in the form of opposed forwardly extending bars, herein of rectangular cross-sectional shape, said bars 11 and 12 being desirably substantially parallel to each other and to elongate handle 8. Intervening base member 13, herein shown of rectangular cross-sectional shape, is attached as by welding to the forward extremities of frame sides 11 and 12. As shown in FIGURE 4, forward surface 14 of intervening base 13 may be serrated or of similarly non-smooth roughened configuration, for example the several teeth-like serrations each extending in the transverse direction between sides 11 and 12 so as to provide a gripping surface for the multi-filament type mop 100 shown in phantom line in FIGURE 4.

30 40 45 50 55 60 65 70 75 80 85 90 95

There is an elongate rod 20 at the forward extremity of mop holder 10, forwardly of intervening base 13, said elongate rod 20 having a captive end 21 and a free end 22. As can be clearly seen in FIGURE 1, the entire elongate body of rod 20, commencing at its pivot point 23 and extending to its free end 22, is of a substantially linear configuration, and said rod 20 terminates as a flange-free end 22. Captive end 21 of elongate rod 20 is pivotably attached to mop holder 10 nearer to first side 11 than to second side 12 and forwardly of forward surface 14. The length of rod 20 is sufficiently long that, when rod 20 is in substantial parallelism with intervening base 13, its free end 22 extends outwardly beyond second side 12. For reasons to be explained later, the captive end 21 of rod 20 is pivotably attached to a threaded stud 25 that extends forwardly of bar 11 and base 13. Stud 25 is threadedly engaged with a threaded internal bore 19 of bar 11, said bore 19 commencing at the forward end of first side bar 11. The forward extremity of stud 25 extends forwardly of bar 11 and is preferably of the clevis configuration shown in FIGURE 2, and captive end 21 is pivotably attached within the clevis as by means of pivot pin 23. Rod 20 has a notched portion 24 nearer to free end 22, herein as a circumferential notch 24 that is located between second side bar 12 and rod free end 22 when said rod is in substantial parallelism with intervening base forward surface 14. The surface of elongate rod 20 may be knurled

or of other non-smooth roughened configuration so as to provide a gripping means between mop 100 and rod 20.

There are means attached to second side 12 for temporarily grasping elongated rod 20 nearer to its free end 22 so as to removably maintain rod 20 in substantial parallelism with intervening base forward surface 14. The grasping means may comprise a latch 30 together with catch 50, said latch 30 being positioned alongside and pivotably attached to second side bar 12. For reasons to be explained later, latch 30 may be pivotably attached to a sideward lug 41 of collar 40 as by means of pivot pin 42. Collar 40 surrounds and threadedly engages a threaded medial portion 16 of second side bar 12, said threaded medial portion 16 being of circular cross-sectional shape. There is an outwardly extending ear 45 attached to second side bar 12 rearwardly of threaded medial portion 16, and ear 45 may have a transverse perforation 46 therethrough.

The rearward extremity 31 of latch 30 extends rearwardly of ear 45, and the lever-like rearward portion of latch 30 includes a slot 32. As can best be seen in FIGURE 3, the width of slot 32 is at least as wide as ear 45, and the elongated length of slot 32 between its upper extremity 33 and its lower extremity is at least twice the length of ear 45.

The inwardly bent free ends 55 of V-shaped catch 50 pivotably pierce both opposed sides of latch 30. When latch 30 is positioned alongside second side bar 12, the pivotably engaged ends 55 are located rearwardly of the pivotal joiner 42 of latch 30 with second side bar 12. The forward extremity 51 of elongate catch 50 extends forwardly of intervening base 13, and the forward extremity 51 surrounds rod 20 at notch 24 to this maintain rod 20 in substantial parallelism with intervening base 13. As can best be seen in FIGURES 2 and 4, the rod 20 when held in parallelism with intervening base 13 removably maintains a typical multi-filament mop 100 at the forward end of mop holder 10 between rod 20 and base 13. As shown schematically in phantom line in FIGURE 3, an appropriately bent length of flexible wire 47 inserted through ear perforation 46 will function as a means to maintain latch 30 tightly against rod 20.

The multi-filament mop 100 shown in phantom line in FIGURE 4 is of the typical commercially-available embodiment which comprises a plurality of layers (herein as three layers), each layer comprising a multitude of hydrophilic flexible filaments spaced transversely between frame sides 11 and 12. Mop 100 comprises a central web portion 105 wherein the respective filaments are integrally joined together by adhesive or by a mechanical inter-weaving, and there are two banks 106 and 107 of loosely arranged filaments on either side of intermediate web portion 105. It is, of course, the two banks 106 and 107 that are used to clean a floor, or whatever surface is to be cleaned, and inter-bank tangling of the several filament members is apt to result during use of the mop 100. Although a new mop can be inserted into the mop holder 10 in a direction normal to intervening base 13, after the mop has been used there is apt to be inter-bank tangling of the filament members and it is thereafter impossible to remove the mop 100 from the mop holder 10 in a direction normal to intervening base 13, unless the filaments are laboriously untangled. However, with the present invention a mop 100 having inter-bank tangling can be readily removed in a direction parallel to intervening base 13 simply by moving latch 30 outwardly from second side 12 as shown in phantom line in FIGURE 1. In so moving latch 30 outwardly, the catch portion 50 of the grasping means moves downwardly until its pivotably engaged ends 55 are below the latch pivot point 42. Then, the operator merely pivots catch 50 outwardly, pivots rod 20 forwardly, and slides a mop 100 rightwardly to remove even a tangled mop from mop holder 10.

Although the mop 100 shown has but three layers of filaments, a mop may contain various numbers of filament layers and filament diameters, and accordingly, the thickness of central web portion 105 may vary from mop to mop. To compensate for the various thicknesses of mop webs likely to be encountered, captive end 21 of rod 20 at rod pivot 23 is adjustably disposed with respect to first side 11 as by means of threaded stud 25, and similarly catch 50 is adjustably disposed with respect to second side 12 as by means of threaded collar 40. Since rod 20 must operatively extend inwardly from first side 11 and since the grasping means must operatively extend outwardly from second side 12, the thread pitches on stud 25 and on threaded portion 16 should be of a relatively small value and preferably of equal values.

From the foregoing, the construction and operation of the mop holder device will be readily understood and further explanation is believed to be unnecessary. However, since numerous modifications and changes will readily occur to those skilled in the art, it is not desired to limit the invention to the exact construction shown and described, and accordingly, all suitable modifications and equivalents may be resorted to, falling within the scope of the appended claims.

25 I claim:

1. A holder for a filament type mop, said holder comprising a frame member including a first side and a second side and an intervening base attached transversely between said first and second sides, said intervening base having a forward surface, an elongate rod positioned forwardly of the frame member intervening base, said elongate rod having a captive end and a free end, the captive end of said elongate rod being pivotably attached to said frame member nearer to the first side thereof, the pivotal connection between the elongate rod and the frame member being located forwardly of and adjustably disposed with respect to the intervening base forward surface, the length of said elongate pivotal rod being sufficient so that the rod free end extends outwardly beyond the frame second side when the elongate pivotal rod is in substantial parallelism with the intervening base forward surface, the entire elongate body of said elongate rod, commencing at its pivotal connection with the frame member and extending to the rod free end, being of a substantially linear configuration including a flange-free end, and means for temporarily grasping said elongate rod nearer to its free end so as to maintain said elongate rod in substantial parallelism with the intervening base forward surface, said grasping means being positioned outwardly from and being attached to the frame second side.

2. The mop holder device of claim 1 wherein the grasping means includes a latch positioned outwardly from and pivotably attached to the frame second side and an elongate catch pivotably attached to the latch rearwardly of the pivotal connection between the latch and the frame second side.

3. The mop holder device of claim 2 wherein the forward surface of the intervening base is of a roughened configuration, wherein the surface of the elongate rod comprises roughened areas to facilitate gripping of a filament type mop between the intervening base and the elongate rod, and wherein the elongate rod has a circumferentially notched portion nearer to the rod free end, said circumferentially notched portion extending outwardly beyond the frame second side when the elongate pivotal rod is in substantial parallelism with the forward roughened surface of the intervening base.

4. The mop holder device of claim 1 wherein the frame member comprises as the first and second sides thereof a pair of opposed side bars including a first side bar and a second side bar; wherein the forward surface of the intervening base includes a plurality of teeth-like serrations extending in the transverse direction between the first and second side bars; wherein the elongate rod has a circumferentially grooved notched portion nearer to the

rod free end, said circumferentially grooved notched portion extending outwardly beyond the second side bar when the elongate pivotal rod is in substantial parallelism with the forward serrated surface of the intervening base; and wherein the grasping means includes a latch positioned outwardly from and pivotably attached to the second side bar and an elongate U-shaped catch attached to the latch rearwardly of the pivotal connection between the latch and the second side bar.

5. The mop holder device of claim 4 wherein the first and second side bars are substantially parallel to each other; wherein the first side bar is provided with a threaded internal bore commencing at the forward end of the first side bar, a stud member threadedly engaged along the first side bar internal threaded bore, the forward end of the stud member being of a clevis configuration; wherein the elongate bar is pivotably connected to the stud member within the clevis portion thereof; wherein a collar member surrounds and is threadedly engaged with a threaded portion of the second side bar; wherein a perforate ear is attached to the outward side of the second side bar rearwardly of the collar member; and wherein

the latch portion of the grasping means is pivotably attached to the collar member, said pivotable latch including a rearwardly extending lever having an elongate slotted portion that is at least twice the length of said ear whereby the ear will protrude through the lever slotted portion when the latch is pivoted toward the second side bar, said perforate ear being adapted to receive a retaining wire to maintain the lever in latched position.
